(57) **CLAIM**

The ornamental design for an automobile, as shown and described.

DESCRIPTION

FIG. 1 is a front view of an automobile showing my new design;

FIG. 2 is a front and left side perspective view thereof;

FIG. 3 is a rear and left side perspective view thereof;

FIG. 4 is a left side view thereof;

FIG. 5 is a right side view thereof;

FIG. 6 is a rear view thereof;

FIG. 7 is a top view thereof; and,

FIG. 8 is a bottom view thereof.

The grey parts of the computer-generated image shown within white broken-line perimeters, illustrate portions of the automobile that form no part of the claimed design. The lightened part of the photographs shown in coarser dot filter within the broken-line perimeter, illustrate a portion of the automobile that forms no part of the claimed design.

1 Claim, 8 Drawing Sheets
